UNITED STATES PATENT OFFICE

EDWARD B. ENTWISLE, OF JOHNSTOWN, PENNSYLVANIA

SWITCH

Application filed August 28, 1931. Serial No. 560,017.

This invention relates to switch operating mechanism and more particularly to an improvement in switch operating mechanism of the type disclosed and claimed in U. S. Patent No. 1,125,957 issued January 26, 1915 to Carroll Burton.

One of the objects of the present invention is to provide an adjustable spring link for said switch operating mechanism.

10 Another object is to provide an improved means of seating the adjustable spring link in said switch operating mechanism.

Another object is to provide a switch operating mechanism including spring links that may be readily assembled and adjusted.

15 Other objects and advantages will be apparent as the invention is more fully disclosed.

In accordance with the objects of the present invention I have devised a novel type of 20 adjustable spring link and means for seating the same within the switch box as will be fully apparent from the following description taken with the accompanying drawings.

Referring to the drawings, Fig. 1 is a plan 25 showing a switch operating mechanism incorporating the elements of the present invention;

Fig. 2 is an enlarged view partly in section of the spring link and spring link seating 30 means of the present invention;

Fig. 3 is a sectional view taken along plane 3—3, Fig. 1;

Fig. 4 is a cross-sectional view of the spring link seating means of the present invention; and

Fig. 5 is a view of the spring link head which is adapted to be seated in the recess shown in Fig. 4.

In Fig. 1 the switch operating mechanism 40 of the present invention comprises a switch base 1 supported in the usual manner upon a road bed including ties 21 upon which is mounted in any convenient manner the switch housing 2. Flanges 3 on the housing 45 2 are adapted to receive a cover (not shown).

The switch operating means comprises the usual type of reach rod 4 seated in the switch base 1 and adapted at one end to be attached to a switch tongue 5 and at the other end to 50 spring link members 6. The ends of the

spring links 6 are adapted to pivot within recesses in the end of reach rod 4 and within recesses or seats in housing 2 so that the reach rod 4 may be freely moved back and forth to either of the two positions indicated in Fig. 1, the compression in the springs of the spring links 6 serving to yieldably retain the switch tongue in the desired switched position.

Heretofore the spring in the spring link 6 has not been made adjustable, and a desired tension could not be obtained therein except by changing the spring strength. I propose to obtain this adjustability of the spring by comprising the spring link of 65 three sections; a threaded bolt section having a spherical head and a plurality of nuts threaded thereon; a helical spring; and a cylindrical shaped end piece section having a flange extension; a rounded end suitable 70 for insertion within the usual grooved opening in the reach rod and having an opposite end adapted to enter the core opening of the helical spring.

The spring link of the present invention is 75 illustrated with particularity in Fig. 2 in which 10 comprises the threaded bolt having a spherical head 11, a plurality of threaded nuts 12 and a washer 13; 14 comprises the helical spring; and 15 comprises the detached 80 end section having a flange 16, a rounded end section 17 and an opposite end section (identified by numeral 15) adapted to enter the core opening of coil 14.

Instead of providing the switch box housing 2 with a molded seat as heretofore, I provide the same with a recess 18 adapted to receive and to seat a hardened steel piece 19 provided with a spherical seat 20 adapted to receive the spherical head 11 of bolt 10 as 85 illustrated in Fig. 2.

In assembling the switch mechanism of the present invention the threaded bolt 10 with the two threaded nuts 12 and washer 13 in position close to the spherical head 11, 90 the spring coil 14 and the end piece 15 are loosely assembled together and placed with hardened steel piece 19 in proper position on each side of throw rod 4 within the housing. Nuts 12 are then drawn up until the result 100

ing compression to the spring coil 14 results in the desired snap in the switching mechanism. To remove either or both the reverse procedure only is necessary.

5 It is apparent that in addition to the marked advantages of ready assembly of parts and adjustability as to spring compression, the use of the end piece 15 provides side-wise flexibility and give which is not inherent in other structures. This facilitates the shifting of throw rod 4 in either direction, there being no resistance due to friction within the movable parts to overcome.

10 From the above description and drawings 15 it is apparent that many modifications and adaptations of the specific embodiment disclosed herein may be made without departing essentially from the nature and scope of the present invention as may be set forth in the 20 following claims.

What I claim is:

1. In a switch mechanism, adjustable 25 spring links each comprising a threaded bolt having a spherical head, a plurality of threaded nuts thereon, a helical spring and an end piece including spring retaining means and means to engage a reach rod.

2. In a switch mechanism, an adjustable 30 spring link comprising a helical spring, a threaded bolt having a spherical head and a body adapted to enter the spring core and a third member having one end thereof adapted to engage and retain one end of said spring and the other end adapted to engage a 35 switch reach rod, and means to adjust the spring compression.

3. In a switch mechanism, an adjustable 40 spring link comprising a helical spring, a threaded bolt having a spherical head and a body adapted to enter the spring core and a third member having one end thereof adapted to engage and retain one end of said spring and the other end adapted to engage a switch reach rod, and means to adjust the 45 spring compression comprising a plurality of threaded nuts on said bolt intermediate the spring end and said bolt head and adapted to be moved along the bolt body threads.

In witness whereof I have hereunto signed 50 my name.

EDWARD B. ENTWISLE.
